UNITED STATES PATENT OFFICE.

FRANK R. COLQUITT, OF HUNTINGTON PARK, AND CLAUD E. CHAPMAN, OF LOS ANGELES, CALIFORNIA.

STEAMER.

1,341,972.

Specification of Letters Patent.

Patented June 1, 1920.

Application filed August 2, 1919. Serial No. 314,949.

To all whom it may concern:

Be it known that we, FRANK R. COLQUITT and CLAUD E. CHAPMAN, citizens of the United States, residing, respectively, at 5 Huntington Park and at Los Angeles, in the county of Los Angeles and State of California, have invented a new and useful Steamer, of which the following is a specification.

10 This invention relates to a utensil for steaming articles of food, and the main object of the invention is to provide a utensil for this purpose which is simple and cheap in construction and efficient and durable in 15 operation.

The accompanying drawings illustrate an embodiment of our invention, and referring thereto:

Figure 1 is a vertical section thereof, and 20 Fig. 2 is a plan view, with the cover partly broken away.

The invention comprises a receptacle *a* having an inner wall 1 and an inner or upper bottom 2, and also having an outer wall 3 and an outer or lower bottom 4, forming a water and steam jacket *b* extending around and below the said receptacle; said inner and outer walls being connected at their upper ends by a web 6 which is 25 preferably formed with a channel 7 which extends around the receptacle *a* and communicates therewith through slots or passages 8 provided at the upper end of inner wall 1, said channel also communicating 30 with the water and steam jacket space *b* through openings 9 in web 6.

A spout 10 for charging and emptying the space *b* of the device is formed as an integral projection from the outer wall 3, 40 and a partition 11 extends downwardly from the adjacent part of said wall, forming a passage 12 which opens at its upper end into the spout 10 and at its lower end into the lower part of the jacket space *b*.

45 The receptacle above described, including the inner and outer walls and bottoms and the connecting web is cast as a single casting of suitable metal, preferably aluminum, the space *b* and passages 9 and 12 being 50 formed by suitable core means. A strut 13

connects the inner and outer bottoms 2 and 4, serving as a brace or support, and also facilitating the casting of the device. The outer and inner walls 3 and 1 are preferably given a slight downward taper to facilitate drawing from the mold. 55

A cover 14 is preferably provided for the device, adapted to fit tightly within an annular shoulder 15 on the web 6, said cover having a rim portion 14' extending over 60 the channel 7 in said web and resting on the upper end portions of inner wall 1, between the slots 8. The central portion of the cover is preferably raised as shown and is provided with a handle 16. 65

In using the steamer, water is poured into the spout 10 to charge the jacket space *b* to any desired extent, for example, to the level indicated by line *c-c* in Fig. 1; and the articles to be steamed being placed in the 70 receptacle and the cover put in place, the steamer is placed on a stove or heater, and steam is generated in the space *b*, and passes through openings 9, groove 7 and passages 75 8 to the receptacle *a* so as to subject the 75 contents of the receptacle to steaming action.

What we claim is:

1. A steamer formed as a single casting of metal having an inner wall and bottom 80 forming a receptacle and an outer wall and bottom forming a water and steam jacket extending below and around said receptacle, a web connecting the upper ends of said inner and outer walls and formed with a 85 channel and with openings establishing communication from said water and steam jacket to said channel and with passages establishing communication from said channel to said receptacle, and a cover extending over said receptacle, said web having a shoulder fitting the rim of said cover. 90

2. A steamer as set forth in claim 1 and in which said outer wall is formed with a spout and with a passage extending downwardly from said spout to the lower part 95 of said water and steam jacket.

3. A steamer comprising an inner wall and bottom forming a receptacle, an outer wall and bottom forming a steam jacket ex- 100

tending below and around said receptacle, a web extending between the upper portions of said inner and outer walls and formed with a channel and with openings establishing communication from said jacket to said channel and with passages establishing communication from said channel to said recep-

tacle, and a cover extending over said receptacle.

In testimony whereof we have hereunto 10
subscribed our names this 24th day of July,
1919.

FRANK R. COLQUITT.
CLAUD E. CHAPMAN.
